UNITED STATES PATENT OFFICE.

AUGUST SCHEUERER, JR., OF HOBOKEN, NEW JERSEY.

MULTIPLE-PRINTING PRESS.

939,553.

Specification of Letters Patent.

Patented Nov. 9, 1909.

Application filed June 21, 1906. Serial No. 322,667.

To all whom it may concern:

Be it known that I, AUGUST SCHEUERER, Jr., a citizen of the United States, and residing at Hoboken, in the county of Hudson and State of New Jersey, have invented 5 certain new and useful Improvements in Multiple-Printing Presses, of which the following is a specification, such as will enable those skilled in the art to which it appertains to make and use the same.

This invention relates to multiple-color printing machines, and the object thereof is to provide a machine of this class with means whereby a series of different colors 15 can be applied successively to the material which is to be printed upon in order to obtain the finished design or representation by a series of overlying tints of different colors; another object being to apply different tints of the same color simultaneously 20 to a number of sheets to be printed upon at each revolution of the form cylinder; another object being to provide means whereby the adjustment of the separate and 25 most essential members of the printing press is facilitated and whereby also the inking mechanism as a whole can be entirely separated from the rest of the printing machine.

30 The invention is fully disclosed in the following specification, of which the accompanying drawings form a part, in which the separate parts of my improvements are designated by suitable reference characters 35 in each of the views, and in which;—

Figure 1 represents a side view of my improved machine; Fig. 2 a longitudinal vertical section of the same; Fig. 3 an end view of the same; Fig. 4 a detail sectional view 40 of a part of the inking mechanism; and, Fig. 5 a section on the line 5—5 of Fig. 4. Fig. 6 is a partial view showing details of construction.

In the drawings 1 is the main frame 45 which supports the form-cylinder 2, the transfer cylinder 3, the paper cylinder 4, the paper roll 5, paper tension 6 and various other adjuncts more specifically referred to below. The shaft 7 of the form-cylinder 2 rests in solid bearings which form part of the main frame 1. The shaft 8 of the transfer cylinder 3 rests in vertically adjustable bearings 9 which can be operated and regulated by means of the hand operated worm gear 10 and which will facilitate the necessary alignment of the cylinder 3 superim-

posed upon the cylinders 2 and 4. The shaft 11 of the paper cylinder 4 rests in horizontally adjustable bearings 12 which consist of the usual brasses and followers with 60 adjusting screws 13 well known in the art. The inking mechanism 14 consists of various fountains and rollers necessary for this class of printing machines and is attached to a separate frame 15. This frame has truck 65 rollers 16 which travel over rails 17 which latter are stationary on the bed plate 18 which also forms the bed plate for the main frame 1. Two lines of rack-gearing 19 are also attached to the bed plate 18 and into 70 which gear the wheels 100 which latter are connected by the transverse shaft 20. One of the gear wheels 100 is driven by means of the pinion 101 which latter can be operated by means of a hand-crank 21 and by 75 means of this series of gearing, the frame 15 and the therewith connected inking mechanism 14 is caused to travel longitudinally over the rails 17 whereby the frame 15 can, at the will of the operator, be brought nearer 80 to or farther from the main frame 1. The object of this construction is to permit an easy access to the inking mechanism and to the form-cylinder. The frame 15 can be locked to the frame 1 as seen in Fig. 2 of 85 the drawings by means of draw-bolts 22 which pass through a pair of lugs 23, one of which is part of either of the frames, or by means of any other suitable locking mechanism.

90 The form-cylinder 2, as shown in the various views of the drawings, is intended for the transference of eight different tints or colors and is served by means of an inking mechanism consisting of eight different sets 95 of inking rollers, fountains etc., and for the sake of illustration the following series of colors are intended to be used in connection therewith, namely, inking rollers 24 supply a light yellow color, inking rollers 25 a dark 100 yellow, rollers 26 light red, rollers 27 dark red, rollers 28 light blue, rollers 29 dark blue, rollers 30 gray, and rollers 31 a brown color. These sets of rollers are placed radially to the axis of the form-cylinder, and 105 as illustrated in detail in Figs. 2, 4 and 5 of the drawings, each consists of the usual fountain 32, ducker 33, distributing inking cylinder 34, riders 35 and form-rollers 36. The shafts 37 of the distributing inking 110 cylinders 34 are placed in radial slots 38 in the frame 15 and extend outwardly of the

same. The shafts 39 of the riders and the shafts 40 of the form-rollers are placed in runways 41 arranged radially to the axis of the form cylinder 2, and both ends of all the 5 shafts 40 are provided with grooved contact rollers 141 which in turn travel over the periphery of multiple grooved guide rollers 42 which latter are fastened to the ends of the form cylinder 2 and rotate with the same 10 for the purpose hereinafter more fully described.

In order to keep all inking rollers concentric to the outer periphery of the form-cylinder, the projecting ends of the shaft 37 of 15 the various distributing inking cylinders, which project outwardly of the frame 15 as described above, are encircled by a semi-circular band 43 as seen in Fig. 1 of the drawings. This band 43, midway is supported at 44, and likewise with its ends 45 20 on the frame 15 and can be placed in proper operative position by means of set-screws 46 which will permit a tightening and loosening of all inking rollers by drawing the 25 semi-circular band 43 toward or away from the vertical joint between the frames 1 and 15. The upper four inking sets 24, 25, 26 and 27 will gravitate toward the center of the form-cylinder, while the lower four inking sets 28, 29, 30 and 31 are adjustable toward the form-cylinder 2 by means of special set-screws 47 which pass through the band 43 and bear upon the projecting shafts of these sets. The set-screws 47 may be dispensed with and a compressing spring 48 35 centrally located at the supporting point 44 may be employed to force the band 43 and the inking rollers inwardly toward the form roller.

40 The circumference of the form-cylinder 2 is divided into as many sections, eight in this case, as there are inking sets, each section being designed to carry one segment form and each form is designed to receive 45 its respective color from one of the inking sets and afterward to transfer the color to a respective section of the transfer cylinder 3. This cylinder 2 is preferably composed of end spiders 49 having a hub 50 and outer 50 circumferential bearing ring 51, or one or more additional spiders centrally located between the end spiders may be employed in cases of exceptional width of the printing 55 press. Mounted on the outer periphery of the bearing ring 51 are the eight segment forms 52, 53, 54, 55, 56, 57, 58 and 59 with a longitudinal open space 66 left between each two adjoining segment forms, it being understood that the peripheral lengths of 60 each segment form as well as its transverse width from end to end are the respective dimensions of the sheet which is to receive the different impressions thereon. As seen in Figs. 4 and 5 each segment form has inwardly extending transverse lugs 60 which

fit in accurately spaced recesses 61 cut into the outer circumference of the bearing ring 51. Set-screws 62 placed in the bearing ring 51 will permit radial adjustment of either end while locking set-screws 63 are employed to facilitate transverse adjustment and also to securely fasten the segment forms into position.

In order to attach the form plate 64 which contains the subject matter that is to be transferred and to be printed in the various colors on the segment forms 52 to 59 inclusive, adjusting follower plates 65 are introduced into the open spaces 66 between the adjoining forms. These plates are provided with a row of buttons 67 to which the form plate 64 can be attached, and a number of set-screws 68 which bear against the rigid sides that form the recess 66 will force the follower plate 65 and the therewith connected form plate 64 outwardly and thereby tighten and rigidly secure the same. Projecting lugs 69 of the bearing ring 51 and fitted in the corresponding recesses 70 of the follower plate 65 hold the latter in its position and prevent radial dislodgment of the same.

As seen in Figs. 3 and 5 of the drawings, each end of the form-cylinder 2 has rigidly fastened thereto by bolts or rivets 71, and 95 concentrically placed to the axis of the shaft 7, a guide roller 42 as above referred to. Each of the guide rollers 42 is provided with a plurality of circumferential ridges 72 and intervening grooves 73, the number of said 100 ridges on each guide roller corresponds with the number of the sets of contact rollers 141 which latter are mounted on the shafts 40 of the form-rollers 36. Three of said contact rollers 141 form a set and each set occupies 105 one of the circumferential ridges 72 of the guide roller 42 on either side of the form-cylinder 2, and upon rotation of the latter the contact rollers 141 will rotate upon their own axis, being held in frictional contact with the guide rollers as above described by means of the encircling band 43 and the therewith connected set screws 47. Each one of the circumferential ridges 72 of the 110 guide rollers 42, as illustrated in Figs. 2, 3 and 4, has at 74 a slight segmental depression which is concentric to the outer periphery of the same and the length of the arc of each of said depressions 74 is equal to the length of the arc of each of the forms 52 to 59 inclusive plus the length of the arc of one of the recesses 66. The radial distances of the ridges 72 and that of the depression 74 are so arranged that the ridges 72 will cause the contact rollers 141 and the therewith connected form-rollers 36 to travel slightly above the outer surface of the form plate 64 attached to the form-cylinder 2, but when the contact rollers 141 travel over the 115 depressed path which coincides with the 120 125 130

surface of the respective form plates, the latter will, during the travel over this depressed path, become subjected to the inking action of the form rollers 24 to 31 inclusive.

- 5 It will thus be seen that during one revolution of the form-cylinder 72 all the inking attachments with their form-rollers will successively be set in operation and that the form plates attached to the segment form 52 can receive the color only from the inking attachment 24, that of 53 from 25, and etc. As shown in Fig. 2 of the drawings the inking attachment 24 is in the act of traveling over the form plate attached to the form 52, while all the other inking attachments which are out of action will be held in suspension above their form plates by reason of the contact rollers 141 riding on the higher ridges 73 of the guide rollers 42.

10 The transfer cylinder 3 is of the usual construction and is subdivided into eight parts respectively numbered 75, 76, 77 to 82, corresponding to the eight subdivisions of the form-cylinder 2, and is of equal diameter thereto, each of the subdivisions is properly rubber blanketed and is adapted to receive the transferring impressions from the form plates of the form-cylinder 2 when revolving in opposite directions to the latter.

15 A paper cylinder 4 has been introduced which is of novel construction and which is designed to receive upon the sheets of paper carried forwardly by the same, the various color impressions brought thereto by the transfer cylinder 3. The circumference of the paper cylinder 4 is proportionate to the form-cylinder and to the transfer cylinder as is $n+1$ to n , namely, its circumference possesses one segmental surface more 20 than that of the form-cylinder, and in this case has nine segments numbered on the drawings 83 to 91, and each two adjoining segments have one intervening open space 92 equal to that of the open space 66 of the 25 form-cylinder 2 and that of the open space 93 of the transfer cylinder 3, and it becomes apparent that in revolving the three cylinders in the direction of the arrows as seen in Fig. 2 of the drawings the segment surfaces 30 will be brought into and out of contact at the same time, and that between cylinders 2 and 3 always the same surfaces will meet, but that between cylinders 3 and 4 successively alternating segment surfaces of 35 the paper cylinder 4 will come in contact with the segment surfaces of the transfer cylinder 3. The recesses 92 are provided with gripping attachments 94 of any approved construction. The paper roll 5, the 40 paper tension 6, the rotary cutter 95, the releasing grip 96 and the take-off 97 are of any of the old approved forms and are not 45 specifically claimed herein.

The fountain 98 with metal roller 99 and 65 distributing roller 102, the latter covered

with mole skin, is introduced as seen in Fig. 2. of the drawings, and the object thereof is to subject the printed sheets, when they have arrived at this point of their travel around the axis of the paper cylinder 4, to the action of a neutralizing solution which latter has the tendency to rapidly dry the last color imparted to the sheet and to place the same in condition suitable to receive the next succeeding color impression. The action and operation of this cylinder is as follows;—The gripping attachment 94 takes hold of the sheet of paper 103, just cut in the proper length by the rotary cutter 95, and the sheet will attach itself in the forward movement of the cylinder 4 to the segment 91 and will receive its first color impression—light yellow—as soon as it comes in contact with the segment 79 of the transfer cylinder 3. The prior sheet resting on the segment 83 is commencing to receive the last color impression—brown—from transfer segment 80 and will become detached therefrom when it arrives at the take-off 96, the last finished printed sheet having become detached prior to this from the segment 90 which as shown in Fig. 2 of the drawing is waiting the reception of a new sheet, with the gripping attachment 104 open, as soon as the latter arrives in the position now occupied by the grip 94. The sheet on segment 84 on its seventh revolution around the cylinder 4 has just received the seventh color impression—gray—the sheet on segment 85, on its sixth revolution around the cylinder 4 has lately finished receiving the sixth color impression—dark blue—and so on. Each one of the sheets of paper makes eight revolutions around the shaft 11 and during each of said revolutions receives one of the sequence of colors and is each time, and when arriving at the neutralizing bath roller 102, subjected to the latter's drying action.

The machinery necessary to operate the gripping and releasing attachment for the sheets is not shown in the drawings and any of the well known devices suitable to accomplish this object may be employed. 110

From the foregoing description it will be seen that the functions of the various cylinders and their adjuncts are positive and accurate in their action and that the object of the invention, namely, to provide a simplified and accurate multiple color printing press with positive operation and of easy adjustment in all its component parts is thereby attained. 120

It becomes apparent that the cylinders or printing presses of this kind can be provided with any number of segment forms and a corresponding number of inking attachments, and that the number of segment forms on the paper cylinder must equal that number plus one additional segment form. 130

It will also be apparent that the style of the cylinders designated as paper cylinders in the foregoing specification can be applied to any other class of multiple-printing machines provided that such cylinder is circumferentially subdivided in segmental parts which in number exceed by one the form and transfer cylinders segmental subdivisions, and where such subdivisions on the paper cylinder or its equivalent coincide in surface extent with the surface extent of the subdivisions of the form and transfer cylinders, and is also equal to the latter's peripheral speed.

15 The class of multiple printing machinery to which my system of multiple-color printing can be applied embraces those used for dry plate printing, surface printing, either from plate or stone, textile printing or any 20 other class of printing known to the graphic arts when used for color printing.

Having fully described my invention, what I claim as new and desire to secure by Letters Patent, is:—

25 In a multiple-color printing machine, a paper cylinder having segmental surface

subdivisions with intervening open spaces which contain gripping attachments adapted to receive and hold the sheets of material designed to be printed upon and placed on 30 said segmental surface subdivisions, means for feeding the paper or other material in sheets from a continuous paper or material roll to the paper cylinder, a supplemental roller placed so as to come in surface contact with each of the printed sheets attached to the paper cylinder a reservoir for supplying neutralizing and drying solution to said supplemental roller, whereby the sheets of the paper are subjected to the action of 40 the neutralizing and drying solution before receiving a second color imprint, substantially as described.

In testimony that I claim the foregoing as my invention I have signed my name in 45 presence of the subscribing witnesses this 18th day of June 1906.

AUGUST SCHEUERER, Jr.
